Primary Examiner — Susan Bennett Hattan*Assistant Examiner* — Omeed Agilee*(74) Attorney, Agent, or Firm* — Gregory S. Darley-Emerson(57) **CLAIM**

The ornamental design for a lid for container, as shown and described.

DESCRIPTION

FIG. 1 is a perspective view of a lid for container;
 FIG. 2 is a front view thereof;
 FIG. 3 is a rear view thereof;
 FIG. 4 is a left side view thereof;
 FIG. 5 is a right side view thereof;
 FIG. 6 is a top plan view thereof;
 FIG. 7 is a bottom view thereof; and,
 FIG. 8 is a bottom perspective view thereof.

The broken lines and the areas within the broken lines depict portions of the lid for container that form no part of the claimed design.
